UNITED STATES PATENT OFFICE.

LEWIS E. MACOMBER, OF NEW YORK, N. Y., ASSIGNOR TO MAYCLESE, A FIRM COMPOSED
OF LEWIS E. MACOMBER AND WILLIAM E. KLEIS, OF NEW YORK, N. Y.

DESIGN FOR A CLOCK-DIAL.

54,105.

Specification for Design.

Patented Nov. 4, 1919.

Application filed June 28, 1919. Serial No. 307,491. Term of patent 7 years.

To all whom it may concern:

Be it known that I, LEWIS E. MACOMBER, a citizen of the United States, and resident of the city of New York, borough of Manhattan, in the county and State of New York, have invented a new, original, and ornamental Design for a Clock-Dial, of which the following is a specification, reference being had to the accompanying drawing, forming a part thereof.

The figure represents a plan view of my design, which consists of a square panel surmounted by a semi-circular panel, the square panel bearing a circular clock dial ornamented with floral designs at each

numeral, and with substantially triangle floral designs in each corner of the square. The semi-circular panel is ornamented by representation of a floral design emanating from a fancy receptacle.

The said design is printed, painted, molded, cast, carved, engraved, stamped, or otherwise marked, upon metal, wood, textiles, paper, glass, horn, bone, or ivory.

What I claim and desire to secure by Letters Patent, is:

The ornamental design for a clock dial substantially as shown and described.

LEWIS E. MACOMBER.

Copies of this patent may be obtained for five cents each, by addressing the "Commissioner of Patents, Washington, D. C."
